UNITED STATES PATENT OFFICE.

WILLIS M. FARR, OF DOWAGIAC, MICHIGAN.

DESIGN FOR A SAND-BAND.

SPECIFICATION forming part of Design No. 33,250, dated September 25, 1900.

Application filed August 18, 1900. Serial No. 27,349. Term of patent 14 years.

To all whom it may concern:

Be it known that I, WILLIS M. FARR, a citizen of the United States, residing at Dowagiac, in the county of Cass and State of Michigan, 5 have invented and produced a new and original Design for Sand-Bands; and I do hereby declare the following to be a full, clear, and exact description of the same, reference being had to the accompanying drawings, forming 10 a part thereof.

Figure 1 represents a rear view of my new design. Fig. 2 is a front view of the same, and Fig. 3 is a bottom view. Fig. 4 is a vertical section.

15 This invention has relation to a novel design for sand-bands, all as will be hereinafter described and shown.

In the drawings the design represents a hood, and the main feature thereof consists 20 of the rounded portion *a*, which intersects the horizontal portion *b* where the latter meets the vertical portion *c*. Projecting from the

inner face are lugs *d d*, which have vertical openings, and the same are arranged on the outside face of the band and on either side 25 of the opening *e*. At right angles to the vertical face of the band and within the hood are two vertical ribs *ff*, which extend at right angles to said face, the upper ends *g g* being rounded inward, while the lower end of each 30 rib is rounded outward, as clearly shown at *h h*. The outline of the band or contour is semicircular in form and has a projection *i* above the opening.

Having thus described my novel sand-band, 35 what I claim is—

The design for a sand-band herein shown and described.

In testimony whereof I affix my signature in presence of two witnesses.

WILLIS M. FARR.

Witnesses:

JOHN S. BURK,
WM. SQUIER.
